APPARATUS FOR FORGING OR FORMING METAL ARTICLES

Filed Oct. 11, 1927

2 Sheets-Sheet 2

UNITED STATES PATENT OFFICE.

FRANK SCOTT, OF SHEFFIELD, ENGLAND.

APPARATUS FOR FORGING OR FORMING METAL ARTICLES.

Application filed October 11, 1927, Serial No. 225,526, and in Great Britain September 2, 1926.

This invention relates to apparatus for forging or forming metal articles having for its object to reduce the cost of production whilst at the same time speeding up the rate 5 of production.

According to this invention the method of forging or forming metal articles consists in first heating metal blanks, transferring them on to a moving unit for subjection thereby to 10 impact against at least one forming die and thereafter automatically effecting the release of the forged articles from the moving unit.

Apparatus for forging metal articles according to the aforementioned method comprises an operable member, a work-holder carried by said member, means for securing the work in the holder, a die positioned so that the work can make contact therewith, and means for automatically releasing the work 20 from the holder after forging.

Means are, or may be, provided for automatically releasing and ejecting the work from the holders after forging.

The dies are, or may be, rotatable or otherwise movable.

Referring to the drawings filed herewith:—

Fig. 1 is an end elevation of one form of apparatus made in accordance with this invention;

Fig. 2 is a plan of same, two of the work-holders being omitted;

Fig. 3 is an elevation of a blank for a "coal cutter pick";

Fig. 4 is an elevation and end elevation of a partly forged blank; and

Fig. 5 is an elevation of a completely forged tool.

a is a rotatable plate mounted on a shaft 40 b and adapted to be rotated in any suitable manner. c, c are holders mounted at intervals on flats d formed on the periphery of the plate, said holders being provided with supporting dies e for the blanks f which may be

45 positioned at an angle inclined to the vertical as shown or at any other suitable angle according to the required formation of the forged article. Each holder is provided with a transverse pin g screwing into the holder

50 and carrying at its outer end an abutment piece h adapted to engage the blank f in the holder, and being provided at its outer end with a crank arm j which is pivotally connected to a spring-pressed forked plunger k

55 mounted on the plate a by a bracket m, said plunger having a roller n at its free end,

adapted to ride over a stationary cam o loosely mounted on the shaft b. The blank in each holder is supported at the bottom on a plunger p engaged by the forked crank 60 lever q of a spindle r mounted in a bearing s on the plate a, said spindle having a free crank arm t held by a spring u anchored to the plate a and which crank arm is adapted to engage, when passing under the centre of the plate a, a catch v fixed on the framing w of the apparatus.

Opposite the periphery of the plate a is suitably mounted upper and lower adjustable die holders 2 and 3, the upper holder 2 70 carrying a pair of forming rolls or dies 4 between or against which the blanks f are adapted on rotation of the plate a to make contact whilst the lower holder 3 carries a forming die 5 against which the blanks, after 75 contacting with the rolls 4, and being partly formed thereby, also contact to be completely forged. The position of the rolls 4 and die 5 in relation to the plate a and the formation of their contacting faces are such 80 as to give the required shape to the blanks.

The holders 2 and 3 are slidably positioned on the framing w of the apparatus by adjustable stops 6.

In operation, the plate is rotated and as 85 the blanks f are thereby carried round in their holders c and caused to make contact or impact with the rolls 4 which, co-acting with the supporting dies e, bend and shape the exposed ends of the blanks to the form shown 90 in Fig. 4 and when said blanks subsequently contact with the lower forming die 5, they are further and completely forged to the finished shape shown in Fig. 5.

A blank is inserted by hand into its holder 95 and on the plunger k connected therewith passing the point 7 of the cam it is released thereby and drops on to the smallest diameter of the cam and in so doing causes the pin g through the medium of the crank arm j to 100 screw into the holder with its abutment piece h in engagement with the blank and thus gripping it tightly prior to it impacting against the rolls 4.

After the blank passes the die 5 the plunger 105 traverses the path 8 of the cam until it again reaches the greatest diameter thereof and in so doing the grip on the blank is released thus leaving it free to fall out. As, however, it may be found that the forged blanks sometimes stick and are thus prevented from falling out, the plunger p is provided for eject-

ing them. This is effected as follows:—when the free end of the plunger *t* comes in contact with the catch *v* said plunger is tilted whereby the spindle *n* is rotated and its crank lever *q* operated so as to push the plunger *p* downwards against the blank which is thereby ejected from the holder *c*.

The crank arm *j* is slotted at its pivotal connection with the forked end of the plunger *k* as seen at 9, a pin 10 on the plunger engaging said slot 9 to permit free movement of the crank arm *j*.

Where desired, a suitable conveyor, shown in dotted lines in Fig. 1, may be provided for receiving the ejected forged articles and conveying them away to a convenient source.

The connection of the plunger *p* and crank lever *q* is of a similar nature to the crank arm *j* and plunger *k* to give free movement.

20 Apparatus made according to this invention, although not shown may be provided with two or more rotatable plates and complementary co-acting dies.

What I claim and desire to secure by Letters Patent is:—

1. Apparatus for forging metal articles comprising a rotatable member mounted on a shaft, work-holders carried by and movable with the rotatable member, a work gripping member movable transversely of each work-holder, a spring-pressed plunger associated with and adapted to operate each work gripping member, a stationary cam mounted alongside the rotatable member and adapted 30 to actuate in turn the spring-pressed plungers for gripping and releasing the work, upper and lower dies positioned with respect to the rotatable member so that the work can make sequential contact therewith on rotation of the rotatable member, means permitting adjustment of said dies, and means for automatically discharging the work from the holders.

2. Apparatus for forging metal articles comprising a rotatable member mounted on a shaft, a plurality of work-holders mounted on the periphery of the rotatable member, supports for the work in said holders, a work gripping member movable transversely of each work-holder, an arm to each work gripping member and extraneous to the work-holders, a stationary cam, a spring-pressed plunger having a pivotal connection with each arm and ridable over a stationary cam on rotation of the rotatable member, dies positioned with relation to said member so that the work can make contact therewith on rotation of the rotatable member, a path on said cam adapted to actuate each plunger in turn for opening the gripping members after contact with the work.

3. Apparatus for forging metal articles comprising a rotatable member mounted on a shaft, a plurality of work-holders mounted 65 on the periphery of the rotatable member,

supports for the work in said holders, a work gripping member movable transversely of each work holder, an arm to each work gripping member and extraneous to the work holders, a stationary cam, a spring-pressed plunger having a pivotal connection with each arm and ridable over a stationary cam on rotation of the rotatable member, dies positioned with relation to said member so that the work can make contact therewith on rotation of the rotatable member, a path on said cam adapted to actuate each plunger in turn for releasing the work from said gripping member after contact with the dies, and means for automatically ejecting the work on its release, said means comprising a plunger located below the work in each holder, a plunger-arm for operating each plunger, a spring-restrained arm connected to each plunger arm and pivotally mounted on the rotatable member, an extraneous catch for operating each spring-restrained arm after passing below the centre of the shaft, said spring-pressed arm in turn actuating said plunger-arm to actuate the plunger located in the work holders for ejecting the work therefrom.

4. Apparatus for forging metal articles comprising a rotatable member, work-holders carried by and movable with the rotatable member, means for securing work in the holders, a die positioned so that the work can make contact therewith on rotation of the rotatable member, means for automatically operating the work securing means so as to 100 first release and then eject the work from the holders after forging, and means for conveying the ejected work away.

5. Apparatus for forging metal articles comprising a rotatable member mounted on a shaft, a plurality of work-holders mounted on the periphery of the rotatable member, supports for the work in said holders, a work gripping member movable transversely of each work holder, an arm to each work gripping member and extraneous to the work holders, a spring-pressed plunger having a pivotal connection with each arm and ridable over a stationary cam on rotation of the rotatable member, dies positioned with relation to said member so that the work can make contact therewith on rotation of the rotatable member, a path on the cam adapted to actuate each plunger in turn for releasing the work after contact with the dies, and means for automatically ejecting the work on its release, said means comprising a plunger located below the work in each holder, a plunger-arm for operating each plunger, a spring-restrained arm connected to each arm and pivotally mounted on the rotatable member,

110 an extraneous catch for operating each spring-restrained arm after passing below the centre of the shaft, said spring-pressed arm in turn actuating the plunger-arm to 120 125 130

cause the plunger located in the work holders to eject the work therefrom, and means for conveying the ejected work away.

6. A machine for swaging articles by wiping contact of blanks with forming means, comprising a work-holder and a die holder in relative movement into and out of swaging relation, said work-holder including a normally closed gripper and an abutment to eject the work normally held fixed against swaging thrust, and automatic means operating successively, upon termination of relative movement of said holders in swaging relation to cause said gripper to open and be held open while said holders are out of swaging relation, and, upon opening of said gripper, to eject the work from the holder.

7. A machine for swaging articles by wiping contact of blanks with forming means, comprising a workholder and a die-holder in continuous relative movement into and out of swaging relation, said work-holder including a gripper for the work and an abutment to hold the work against swaging thrust, elastic means tending to hold said gripper closed, elastic means tending to hold said abutment in position to sustain swaging thrust, means acting against said first-named elastic means upon termination of relative swaging move-

ment of said holders, to open and hold open 30 said gripper, and means acting against said second-named elastic means after opening of the gripper to cause said abutment to eject the work.

8. Apparatus for forging metal articles 35 comprising a rotating member mounted on a shaft, a plurality of work-holders mounted on the periphery of said rotating member, means for securing work in the work-holders, means for ejecting work from the work-holders, a die-holder supported for movement toward and from said shaft, a second die-holder carried by said first-named die holder and movable thereon toward and from said shaft, means adjustable to limit the positions of 45 said die-holders relatively to said shaft and to each other to insure proper sequential swaging contact of dies held by said die-holders with work carried by said work-holders, and automatic means for opening 50 said workholder upon termination of each swaging act and holding it open until the beginning of a new swaging act, and for ejecting the work upon opening of the workholder.

In testimony whereof, I affix my signature.

FRANK SCOTT.
